United States Patent Office

Des. 195,893
Patented Aug. 6, 1963

195,893

SPECTACLE FRAME

Edith J. Pitts, Attleboro, Mass., assignor to Universal Optical Company, Inc., Providence, R.I., a corporation of Rhode Island

Filed July 25, 1961, Ser. No. 66,056

Term of patent 14 years

(Cl. D57—1)

FIG. 1.

FIG. 3.

FIG. 4.

FIG. 2.

FIG. 1 is a front elevational view of a spectacle frame embodying my new design;

FIG. 2 is a side elevational view thereof;

FIG. 3 is a cross-sectional view through the frame taken on the line 3—3 of FIG. 1;

FIG. 4 is a cross-sectional view through the temple of the frame taken on line 4—4 of FIG. 2.

The dominant features of my design reside in the portions shown in full lines.

I claim:

The ornamental design for a spectacle frame, substantially as shown and described.
